US00D974534S

(12) **United States Design Patent** (10) **Patent No.:** **US D974,534 S**
Chen (45) **Date of Patent:** **** Jan. 3, 2023**

(54) **EXTENSION SHOWER ARM**

(71) Applicant: **Guangdong Heshan Shanshui Sanitary Ware Co., Ltd.**, Jiangmen (CN)

(72) Inventor: **Yuanguang Chen**, Jiangmen (CN)

(73) Assignee: **Guangdong Heshan Shanshui Sanitary Ware Co., Ltd.**, Jiangmen (CN)

(**) Term: **15 Years**

(21) Appl. No.: **29/852,223**

(22) Filed: **Sep. 5, 2022**

(51) LOC (14) Cl. **23-01**

(52) U.S. Cl.

USPC **D23/255**; D23/249; D23/264

(58) **Field of Classification Search**

USPC D23/213, 220, 222, 249, 255, 262, 263,

D23/266

CPC B05B 15/08; B05B 15/14; A47K 10/40;

A61B 6/00

(57) **CLAIM**

The ornamental design for an extension shower arm, as shown and described.

DESCRIPTION

FIG. 1 is a front perspective view of an extension shower arm, showing my new design;

FIG. 2 is a rear perspective view thereof;

FIG. 3 shows the invention in a state of use;

FIG. 4 is a front view of FIG. 1;

FIG. 5 is a rear view of FIG. 1;

FIG. 6 is a left side view of FIG. 1;

FIG. 7 is a right side view of FIG. 1;

FIG. 8 is a top view of FIG. 1; and,

FIG. 9 is a bottom view of FIG. 1.

The broken lines in the drawings show environmental portions of the extension shower arm and form no part of the claimed design.

1 Claim, 9 Drawing Sheets
